UNITED STATES PATENT OFFICE.

ULISSES G. ROGERS, OF COLUMBUS, OHIO, ASSIGNOR TO JACOB BERNHARD,
OF COLUMBUS, OHIO.

ELECTRIC FUSE.

No. 851,082.

Specification of Letters Patent.

Patented April 23, 1897.

Application filed May 17, 1903, Serial No. 317,474.

To all whom it may concern:

Be it known that I, ULYSSES G. ROGERS, a citizen of the United States, residing at Columbus, in the county of Franklin and State of Ohio, have invented a certain new and useful Improvement in Electric Fuses, of which the following, taken in connection with the accompanying drawings, is a description.

10 Heretofore considerable trouble and expense has been occasioned by the arcing of the electric current through the gases generated by the fusing of the fuse-wire.

15 The object of the present invention, therefore, is to provide an improved fuse in which these objections are overcome.

The invention consists in the construction hereinafter described and claimed.

20 In the accompanying drawings, Figure 1 is a sectional view of the shell, the contained parts being in full. Fig. 2 is a cross-section on the plane x x , Fig. 1. Fig. 3 is a detail illustrating how the ribbons of which the cartridge-filler is formed are folded to form cells 25 or pockets.

25 In the several views, 1 designates the cylindrical portion of the cartridge or shell, which will preferably be formed of fiber or other material that is a poor conductor of 30 electricity.

2 2 are metallic caps secured to and covering the ends of the shell or cartridge. These caps have hooks 2^a 2^b, by means of which the device is electrically connected to the terminals between which the fuse is to be inserted.

35 3 designates the fuse-wire, which consists, as usual, of a short piece of wire of soft metal, adapted to melt when the electric current exceeds a given strength.

40 4 designates the filler or device for dividing the interior of the shell into pockets. This constitutes the principal feature of my invention and, as shown, is made up of two strips or ribbons of rather stiff but flexible

45 non-conducting fiber interfolded together by bending them back and forth transversely on each other to form a flexibly and elastically

connected tier or row of pockets, each pocket being square form in outline closed at two edges. In the construction shown the filler 50 is made of such size that it just fits at its corners in the shell. The filler is perforated longitudinally, and the fuse-wire 3 passed through and connected with the caps 2^a 2^b.

From the construction described it will be 55 observed that the chamber formed by the shell is divided along its axis by numerous walls. These walls present in the aggregate a large surface, tending to absorb and disperse the heat generated by the fusing of the 60 conductor. They also split up the cylinder of vapor generated and prevent the arcing of the current through the vapor.

The construction is susceptible of modification without departing from the gist of the 65 invention.

What I claim, and desire to secure by Letters Patent, is—

1. In an electric fuse, the combination with an inclosing shell for the reception of the 70 fuse-wire, of an arc-preventing device within said shell consisting of strips of non-conductor of electricity interfolded and forming pockets closed at two edges, said pockets standing transversely of the shell. 75

2. In an electric fuse, the combination with an inclosing shell for the reception of the fuse-wire, of an arc-preventing device within said shell consisting of two strips of non-conductor of electricity bent back and forth 80 transversely on each other to form pockets, said pockets dividing the interior of the shell transversely.

3. In an electric fusing device, the combination of a shell or holder, a fusing-wire, and 85 a filler for said shell consisting of strips or ribbons of a non-conductor of electricity interfolded to form pockets which stand transversely of the fusing-wire.

ULYSSES G. ROGERS.
